United States Patent Office.

IMPROVEMENT IN FEMALE SYRINGES.

SIMON M. LANDIS, OF PHILADELPHIA, PENNSYLVANIA.

Letters Patent No. 60,526, dated December 18, 1866.

The Schedule referred to in these Letters Patent and making part of the same.

TO WHOM IT MAY CONCERN:

Be it known that I SIMON M. LANDIS, of the city and county of Philadelphia, and State of Pennsylvania, have invented a new and improved "Female Syringe;" and I do hereby declare that the following is a full and exact description thereof, reference being had to the accompanying drawings and letters of reference marked thereon.

Figure I represents the syringe bulb tube, made of metal, rubber, or any other suitable material. *a a* constitute the increased size of bulb, which is longer and more extensive than other syringe tubes. *b b* constitute the new funnel-shaped cavities, without or with communicative grooves, as shown in drawing marked *;*; which are entirely new, and are very much superior to the old-fashion parallel, small openings or holes. In the centre of the funnel cavities very small holes are made to connect with the main hole, A. The benefits of these funnel-shaped cavities and grooves are, first, should the tube rest against the flesh or membranes of the vagina, the flow of water is stopped in the use of the old syringe tubes; but in my new one such cannot be the case; but wherever the tube may rest, the current of fluid thrown will flow in all directions. Moreover, this improved syringe tube may contain from twenty to fifty funnel cavities and holes, (or more or less,) whilst other tubes have seldom more than from four to eight holes, and no funnel-shaped cavities nor grooves. C represents the end to which the hose or gum pipe is attached, when used as a "female hose syringe." But the inventor claims the right to attach this end of the improved female syringe, by screw or otherwise, to other syringes, in any manner.

Figure II represents a new, novel, and convenient apparatus for securely attaching the hose syringe to spigots of any and every size and shape. R R constitute a metallic or gutta-percha box. To the inferior end, at *o*, the leather or gutta-percha pipe or hose is attached, and *t t t* constitute the walls; *j j*, the rim, to which is fitted a corresponding ring, *i i*, which is more fully represented in Fig. III, *i i*, which is attached to the rim *j j* in Fig. II; and *s s* constitute the screws which hold the ring and rim together. Between the ring, *i i*, and rim *j j*, is placed a gutta-percha washer, (see Figure IV, letter K,) through the centre of which a round hole (of various sizes to suit the spigots) is made at *r*. The four small holes, *v v v v*, are made for four screws, which attach rim *j j* to ring *i i*.

Figure III represents the superior view of ring *i i*, in which are seen the four screws, *s s s s*, and also two eyes or ears, *e e*, for a handle, like that of a common bucket, *h h*, to which a common cord, C, is attached; and to the end of said cord a light weight, *p*, is attached. This cord is used by winding it around the spigot several times, when the weight *p* will prevent the cord from unravelling or slipping, and thus the box cannot slide or come off of the spigot by the force of water, which is nearly always the case in attachments without screws.

Any skilled mechanic can easily ascertain from the foregoing description how every part of this improved female syringe and spigot-box are constructed; therefore further instruction would be useless, only to express that—

Figure V represents the hose or pipe.

Figure VI represents the complete combination of syringe bulb tube, with funnel-shaped cavities, (and a few grooves,) hose or spigot-box, washer handle, and cord and weight, ready for use.

The advantages of this syringe over all others in use are numerous: first, in female complaints, like the whites, ulceration, &c., it is necessary that a copious current of water be thrown directly all over the walls of the vagina at once. This instrument will do it effectually, on account of its increased dimensions and novel construction. In flooding or uterine hemorrhages it is far superior to all others. In preventing conception it stands unrivalled. It need not only be applied to bath or hydrant spigots, but can be applied to all syringes or force-pumps of sufficient magnitude to give large enough current of fluid (whether pure water or medicinal preparation) to supply the improved tube. All other syringes are baby inventions, being inefficient to supply the vaginal tube with an ample quantity of fluid.

What I claim as my invention, and desire to secure by Letters Patent, is—

The funnel-shaped cavities, with or without grooves of the syringe bulb tube. Also the box, applicable to spigots of any size, in combination with syringe bulb tube, as herein described.

SIMON M. LANDIS.
